UNITED STATES PATENT OFFICE.

JOHN H. BREWER, OF LOUISVILLE, KENTUCKY.

FRAME.

1,227,577.

Specification of Letters Patent. Patented May 29, 1917.

Application filed October 28, 1916. Serial No. 128,816.

To all whom it may concern:

Be it known that I, JOHN H. BREWER, a citizen of the United States, residing at Louisville, in the county of Jefferson and State of Kentucky, have invented certain new and useful Improvements in Frames, of which the following is a specification, reference being had to the accompanying drawings.

10 This invention relates to certain improvements in frames and has relation more particularly to a frame subjected to opposing forces or is subjected to pressure toward the center such as in window screens or the like; and it is an object of the invention to provide a frame having novel and improved means whereby the same may be reinforced against such forces or pressure.

It is also an object of the invention to 20 provide a novel and improved frame of this general character which may be readily and conveniently extended or contracted in accordance with the requirements of practice and whereby the same may be conveniently 25 and effectively held in its various adjusted positions.

It is also an object of the invention to provide a novel and improved frame of this general character wherein a covering 30 is adapted to be detachably connected, said covering being as desired and such as reticulated fabric when it is desired to employ the frame as a screen or said fabric may be as desired as it has been fully demonstrated in practice that my improved frame can be employed with advantage in displaying emblems, advertising matter, or the like.

The invention consists in the details of 40 construction and in the combination and arrangement of the several parts of my improved frame whereby certain important advantages are attained and the device is rendered simpler, less expensive and otherwise more convenient and advantageous for use, all as will be hereinafter more fully set forth.

The novel features of the invention will hereinafter be definitely claimed.

50 In order that my invention may be the better understood, I will now proceed to describe the same with reference to the accompanying drawings, wherein—

Figure 1 is a view in elevation illustrating a frame constructed in accordance with an embodiment of my invention;

Fig. 2 is an elevational view opposite to that shown in Fig. 1 and disclosing a fragment of fabric applied thereto;

Fig. 3 is a transverse sectional view taken 60 through the device as herein embodied;

Fig. 4 is a fragmentary view in elevation illustrating one of the plates as herein embodied with which a bracing member or rod coacts;

Fig. 5 is a fragmentary view in elevation illustrating a slightly modified form of my invention; and

Fig. 6 is an elevational view of the opposite side of the device as disclosed in Fig. 5. 70

As disclosed in Figs. 1 to 4, my improved frame comprises the longitudinal members A and the transverse members B, each of said members including two sections 1 and 2, having their adjacent end portions in 75 overlying relation and are provided with registering elongated slots 3 through which is directed the clamping member 4, said clamping member 4 being herein disclosed as a conventional bolt and coacting nut. By 80 this arrangement it will be perceived that the members 1 and 2 may be readily adjusted one relative to the other as the requirements of practice may necessitate and be effectively maintained in such adjusted 85 relation.

The ends of the members A and B are in overlying relation and pivotally connected, as at 5, whereby it will be perceived that the frame may be adjusted to fit 90 within an opening that is not of the same size at each end or at each side.

Each of the clamping members 4 is carried by a plate 6 provided adjacent its opposite ends with the lugs 7 overlying the 95 inner edges of the overlapping portions of the sections 1 and 2 of a member A or B, whereby said sections are effectively held against pivotal movement about the clamping member. The intermediate portion of 100 the plate 6 adjacent its inner margin is provided with the bracket 8 extending in a direction opposite that of the lugs 7 and said bracket 8 is provided with the open slot 9 adapted to receive an extremity of a brace 105 rod R, said brace rod being provided with an annular groove 10 into which the marginal portions of the slot 9 are arranged in order to hold the rod R against longitudinal movement.

The rod R coacts with alined brackets 8 and as herein disclosed two rods R are

- employed disposed substantially in perpendicular relation one to the other, although the relative angle of said rod is determined by the adjustment of the members A and B.
- 5 After a rod has been operatively engaged with its coacting brackets 8, the slots 9 of said brackets are adapted to be closed in any desired manner as indicated at 11, in order to prevent accidental displacement 10 of the rod.
- Each of the rods R as herein embodied comprises two sections 12 and 14, one of said sections, as 12, being provided in its end with a socket 15 into which is adapted 15 to be threaded the extension 16 of the section 14. By this arrangement each of the rods R may be longitudinally extended or retracted in accordance with the adjustment of the members A and B and it will 20 also be perceived that the rods serve to effectively brace the frame against opposing forces or where pressure is exerted toward the center of the frame especially when the device is employed as a window screen.
- 25 As herein embodied, the inner longitudinal margins of the members A and B are provided with the restricted openings 17 to afford means whereby a suitable fabric may be laced to the frame. The fabric 30 may be of any character desired and depending upon the use to which the frame is adapted to be put as I have found in practice that my improved frame is particularly advantageous for use in window screening, 35 displaying advertising matter, or the like. If preferred the fabric may be clamped to the members A and B and in which event blocks 18 are employed to force the fabric F within the recesses 19 produced in the 40 outer longitudinal margins of the members A and B, as particularly illustrated in Fig. 2, and it will be self-evident that other means may also be employed for removably securing a fabric to the frame.
- 45 In the form of invention illustrated in Figs. 5 and 6, the overlapping portions of the sections 1^a and 2^a are provided with a plurality of slots 3^a and clamping members 4^a, said slots 3^a and clamping members 4^a being arranged at opposite sides of the sections 1^a and 2^a. By this arrangement the plates 6^a do not require the lugs 7 as referred to relative to the plates 6.
- I also find it of advantage to interlock
- with the lapping portions of the rods R the 55 annular tie member 20 which serves to prevent buckling or relative separating movement between the overlying portions of said rods R under normal conditions.
- From the foregoing description, it is 60 thought to be obvious that a frame constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof 65 and for this reason I do not wish to be understood as limiting myself to the precise arrangement and formation of the several parts herein shown in carrying out my invention in practice, except as hereinafter 70 claimed.
- I claim:
1. A frame comprising members, brackets secured to said members intermediate the lengths thereof, brace rods connected 80 to opposed brackets, said members and brace rods being longitudinally adjustable, and clamping means for holding the members in their adjusted position, said clamping means also serving to hold the brackets in 85 applied position upon the members.
2. A frame comprising members, brace members interposed between opposed members of the frame, the intermediate portion of said brace members being in overlying 90 relation, and a tie member coacting with the overlying portions of the brace members.
3. A frame comprising members, brackets secured to said members intermediate the lengths thereof, brace rods in swiveled 95 connection with opposed brackets, said members and brace rods being longitudinally adjustable, and clamping means for holding the members in their adjusted position, said clamping means also serving to hold 100 the brackets in applied position upon the members.

In testimony whereof I hereunto affix my signature in the presence of two witnesses.

JOHN H. BREWER.

Witnesses:

H. J. TILFORD,
N. L. PILSON.
